Gregory R. Everman(57) **CLAIM**

The ornamental design for a baseball pitching target, as shown and described.

DESCRIPTION

FIG. 1 is a top, front, left side perspective view of a baseball pitching target having a plurality of openings at which a person may aim a baseball;

FIG. 2 is a front elevational view thereof;

FIG. 3 is a rear elevational view thereof;

FIG. 4 is a top plan view thereof;

FIG. 5 is a bottom plan view thereof;

FIG. 6 is right side view thereof;

FIG. 7 is a left side view thereof; and,

FIG. 8 is a top, front, left side perspective view of a baseball pitching target having a plurality of openings at which a person may aim a baseball, as shown in deployed position attached to a structure.

The broken lines within the front surface in FIGS. 1, 2 and 8 are included for the purpose of representing surface portions and details that form no part of the claimed design. The other broken lines shown in FIG. 8 are directed to environmental support structure that likewise forms no part of the claimed design.
